United States Patent Office

Des. 186,238
Patented Sept. 29, 1959

186,238

COFFEE MAKER OR SIMILAR ARTICLE

Paul O. Rawson, Jr., Trumbull, Conn., assignor to General Electric Company, a corporation of New York

Application July 28, 1958, Serial No. 51,972

Term of patent 14 years

(Cl. D44—26)

Fig. 1 is a side elevational view of a coffee maker embodying my new design;

Fig. 2 is a top plan view thereof;

Fig. 3 is a rear elevational view thereof, and

Fig. 4 is a perspective view thereof.

The dominant features of the design reside in the portions shown in full lines.

I claim:

The ornamental design for a coffee maker or similar article, substantially as shown and described.
